UNITED STATES PATENT OFFICE

CHARLES F. RICHARD, OF BATTLE CREEK, MICHIGAN, ASSIGNOR TO JOHNSON AUTOMATIC SEALER CO., LTD., OF BATTLE CREEK, MICHIGAN, A PARTNERSHIP ASSOCIATION LIMITED, OF MICHIGAN

CARTON FEEDING MACHINE

Application filed April 2, 1932. Serial No. 351,929.

This invention relates to carton feeding machines and while capable of general use is particularly adapted for feeding cartons to a carton sealing machine or other instrumentality to be fed.

One object of the invention is to provide a carton feeding machine which enables the cartons to be fed from a plurality of sources of supply to a single instrumentality to be fed.

Another object of the invention is to provide a carton feeding machine which feeds the cartons continuously from separate sources of supply to the carton sealing machine or other instrumentality to be fed.

Another object of the invention is to provide a carton feeding machine which feeds the cartons from separate sources continuously, and at high speed, to a continuously operated carton sealing machine or device with which said carton feeding machine is associated.

Another object of the invention is to provide a carton feeding machine which feeds cartons from a plurality of separate sources of supply into pockets that carry the cartons at high speed to the carton sealing machine or other device to be fed.

Another object of the invention is to provide a carton feeding machine which embodies a plurality of feeders and movable pockets compactly arranged and readily adapted for association with the carton sealing machine or other device to be fed.

Another object of the invention is to provide a carton feeding machine which is simple in construction, efficient in operation, and relatively inexpensive to manufacture, install, and maintain in operation.

Other objects of the invention will appear as the following description thereof proceeds, and in order to more clearly understand said invention, reference may be had to the appended drawings which illustrate one embodiment of the inventive idea.

In said drawings—

Fig. 1 is a side view of a carton sealing machine equipped with mechanism embodying the present invention;

Fig. 2 is a top plan view, with parts omit-

ted, of the machine and mechanism shown in Fig. 1; and

Fig. 3 is a vertical longitudinal sectional view on the line 3—3 of Fig. 2.

Referring to the drawings, wherein like characters designate like parts throughout the several views, said drawings show a carton sealing machine, a plurality of movable pockets adapted to support and carry cartons for transfer to said machine, and a plurality of carton feeding mechanisms for delivering cartons into said pockets. These instrumentalities will be described in the order named, and are preferably operated and constructed as follows.

The carton sealing machine includes upper and lower side frame members 5 and 6, respectively, duplicated at opposite sides of the machine and joined together by upper cross members 7, 8 and lower cross members 9, 10. The lower cross members 9, 10 are bolted or otherwise suitably secured to legs 11, 12 disposed in pairs at opposite sides of the machine, respectively, and supporting the described framework therefor. The legs 11, 12, in turn, are bolted or otherwise suitably secured to the machine foundation 13, one of the legs 12 having an extension 14 on which is bolted or otherwise suitably secured, as at 15, 15, a bracket 16.

Supported on the bracket 16 is an electric motor 17 which serves to drive the various movable parts of the machine. This motor 17 is supplied with electrical current from any suitable source, and the operation of the machine may be controlled either by a switch for said motor, or by a separate, manually operated clutch, or both. The control device or devices just mentioned are of the usual type provided on machines of this character, and it is therefore unnecessary to illustrate and describe the same.

Fixed on the armature shaft 18 of the motor 17, is a pulley 19 around which passes a belt 20 that also passes around a pulley 21. Tension on the belt 20 may, if desired, be maintained by a roller 21' that is engaged by said belt and supported on a bracket 22 bolted or otherwise suitably secured to the lower side frame 6 adjacent the motor 17. The

- pulley 21 is fixed on a shaft 23 which extends transversely of the machine and is journaled in suitable bearings on the framework thereof. Fixed on the shaft 23 is a pulley 24 around which passes a belt 25 that also passes around a pulley 26. Tension on the belt 25 may, if desired, be maintained by a roller 25' engaging said belt and journaled on an arm 25" mounted in any suitable manner on the machine framework. The pulley 26 is fixed on a shaft 27 that extends transversely of the machine and is journaled on the described framework at the top thereof. Fixed on the shaft 27 is a pulley 28 around which passes a belt 29 that also passes around a pulley 30. Tension on the belt 29 is regulated by a roller 29' which engages said belt and is adjustably mounted on a bracket 29" bolted or otherwise suitably secured to the machine framework. The pulley 30 is fixed on a shaft 31 that extends transversely of the machine at its forward end and is journaled in suitable bearings on the framework thereof.
- Fixed on the shaft 31 are sprockets 32 around which pass chains 33 that also pass around sprockets 34. The sprockets 34 are fixed on a shaft 35 which is journaled in suitable bearings on a cross member 36. The cross member 36 is disposed between and secured to, upper and lower ways 37 and 38, respectively, and the chains 33, through the described connections therefor with the motor 17, travel continuously along said ways during the operation of said motor.
- Fixed at intervals along the chains 33 are a plurality of carton supports or forms 39, the faces of which engage the ways 37 and 38 to hold said supports or forms in proper position as they travel continuously with the chains 33. The supports or forms 39 are in accordance with the present invention, successively supplied with cartons 40 by a plurality of pockets indicated broadly at 41, 41' and from which the cartons are transferred to said supports or forms. These pockets are preferably operated and constructed as follows.
- Fixed on the continuously driven shaft 35 is a sprocket 42 around which passes a chain 43 that also passes around a sprocket 44 that is fixed on a shaft 45 extending at right angles to the carton sealing machine and in parallel relation with the shaft 35. This shaft 45 is journaled in suitable bearings on a substantially rectangular frame which is indicated broadly at 46 and extends at right angles to the conveyor ways 37, 38. This frame includes the usual supporting legs 47 which are joined together by upper and lower cross members 48 and 49, respectively, and said frame serves to support the movable pockets 41, 41' and devices associated therewith.
- Fixed on the shaft 45 is a bevel gear 50 that meshes with a similar gear 51 which is fixed on a vertical shaft 52 journaled in suitable bearings on the frame 46. The frame 46 also has journaled in suitable bearings thereon, vertical shafts 53, 54, 55. Fixed on the shafts 52, 53, 54, 55, are sprockets 52', 53', 54', 55', respectively, and passing around said sprockets is a continuously driven chain 56 on which the pockets 41, 41' are secured to stand vertically and travel continuously with said chain. The chain 56 has all of its reaches disposed in a substantially horizontal plane and said chain and the sprockets around which it passes could, if desired, be replaced by a belt and pulleys, respectively. The pockets 41, 41' are all constructed substantially alike and each of the same preferably includes the following devices.
- For each pocket there are provided relatively movable parts 57, 58 that form opposed carton supporting portions of the pockets adapted to be opened and closed relatively. The parts 57, 58 are fixed in spaced superposed relation respectively, on shafts 59, 60 that are journaled in suitable bearings on a bracket 61 secured to the chain 56. The pocket is normally closed by springs 62, 63 (Fig. 1) which have their opposite ends secured to the shafts 59, 60 and the bracket 61. These springs also provide for opening the pockets to receive the carton. After the carton has been introduced into the pocket and the latter is closed, the springs 62, 63 act on the parts 57, 58 so that they yieldably support the carton in the pocket.
- Fixed on the shafts 59 near the upper ends thereof, are arms 65, 65', the arms 65 all extending in a single substantially horizontal plane, and the arms 65' all extending in a single similar plane spaced above that in which the arms 65 extend. The arms 65 have journaled on the free ends thereof rollers 66, and the arms 65' have journaled on their free ends rollers 66'. The shafts 60 of the pockets have fixed on the lower ends thereof arms 67 all extending in a single substantially horizontal plane and carrying rollers 68. The continuously traveling chain 56 and the pockets secured thereto, are guided and maintained in proper position by ways 69, 70, 71, 72, that are bolted or otherwise suitably secured to the frame 46 and form a substantially rectangular structure.
- Bolted or otherwise suitably secured in spaced superposed relation on the machine framework, are a pair of substantially rectangularly endless tracks or rails 73, 74, that are engaged by the rollers 66, 66', respectively. These rails are provided with cam portions 75, 76 and 77, 78, respectively, the latter cam portions extending past a carton feeding mechanism which is indicated broadly at 79 and disposed at one side of the frame 46 in spaced, parallel relation with the carton sealing machine. A second carton feeding mechanism which is indicated broadly at 80, is

disposed at the opposite side of the frame 46 and also extends in spaced, parallel relation with said carton sealing machine. The pockets 41, 41' alternately receive cartons from said feeding mechanisms and pass the same successively during their travel with the chain 56. For this purpose, the cam portions 75, 76 and 77, 78 of the rails 73, 74, act through their engagement with the rollers 66, 66', respectively, to open all of the pockets and hold them open until they reach the carton feeding mechanism 79. This mechanism is timed to deliver cartons into alternate pockets indicated, for example, by the reference character 41, and to permit alternate pockets indicated, for example, by the reference character 41', to pass by said mechanism without receiving cartons therefrom. Each pocket 41, after receiving a carton from the feeding mechanism 79, is closed to yieldably grip and support the carton in the pocket. For this purpose, the rail 73 is provided beyond the cam portion 77 thereof, with a cam portion 79a which, when engaged by the roller 66 of a pocket, enables spring 62 thereof to immediately swing the lever 65 and the parts 57 in a clockwise direction (Fig. 2), thereby closing the pocket and yieldably supporting the carton between the opposed parts 57, 58 of the pocket. The parts 57 of the pockets, except at one point in their travel, are closed by the action of the springs 62, said parts normally standing at right angles to the brackets 61 and the springs 62 being strong enough to resist appreciable movement of the parts 57 when they engage the carton delivered forwardly thereof into the pockets by the feeding mechanisms 79, 80.

The alternate pockets 41 traveling successively past the cam portion 79 of rails 73 are retained closed by engagement of the rollers 66 with straight portions of said rail extending between the cam portion 79 and the cam portion 75. The alternate empty pockets 41' that pass the carton feeding mechanism 79, are retained in open position by engagement of the rollers 66' with cam portions 81, 82, 83, 84, of the rail 74. These cam portions through their engagement with the rollers 66', act to retain the arms 65' and the parts 57 of the alternate pockets 41' against closing movement until said pockets have been supplied with cartons by the carton feeding mechanism 80. After each pocket 41' receives a carton from the carton feeding mechanism 80, the roller 66' of said pocket engages a cam portion 85 of the rail 74. This cam portion 85 is formed to permit the springs 62 of the pockets 41' to close said pockets successively by swinging the arms 65' and the parts 57 of said pockets in a direction opposite to that of their opening movement.

It will be understood, from the foregoing, that the carton feeding mechanism 80 is timed to successively deliver cartons into

the alternate pockets 41' and to permit the alternate pockets 41 having cartons supported therein, to pass successively without interruption past said feeding mechanism. The parts of the carton feeding mechanism 79 are duplicated in the carton feeding mechanism 80, and have like reference characters which in the case of the carton feeding mechanism 80, are primed to differentiate the two mechanisms. The carton feeding mechanisms 79, 80 being identical in their construction and operation it is therefore only necessary to describe one of said mechanisms.

The carton feeder 79, for example, is supported on a suitable framework including opposed side members 86 arranged in spaced relation and supported at their opposite ends by legs such as indicated at 87 (Fig. 3). These legs are bolted or otherwise suitably secured to the machine foundation 13 and the frames and legs at the opposite sides of the feeder are connected together by upper and lower cross members such as indicated at 88 and 89, respectively. Journaled in suitable bearings on the front pair of legs 87 is a shaft 90 having fixed thereon a sprocket 91 around which passes a chain 92. This chain 92 is controlled and intermittently driven by any suitable devices (not shown) for these purposes.

Fixed in spaced relation on the shaft 90 are bevel gears 93 (Figs. 2 and 3) that mesh with similar gears 94, respectively. The gears 94 are fixed on vertical shafts 95 that are journaled in suitable bearings on the front cross member 88 of the feeder. Fixed on the shafts 95 are sprockets 96 around which pass chains 97 that also pass around sprockets (not shown) which are journaled in any suitable manner on the end of the feeder opposite that carrying the shafts 95 and the sprockets 96. The intermittently driven chains 97 have secured thereon at intervals, transversely aligned stops 98 in front of which may be placed followers 99 adapted to stand on and travel along rails 100 extending longitudinally of the feeder. The rails 100 project forwardly of the feeder below the pockets 41, 41' and support open cartons delivered by a continuously moving knife 101 into alternate pockets 41.

A stack of cartons 102 is placed on the rails 100 in front of a follower 99 and intermittently advanced by the chains 97 as the cartons are successively separated from the stack by the knife 101. Each carton separated in the manner just mentioned, is advanced by the knife 101 through guide fingers 103, 104 which are supported in any suitable manner by the forward part of the feeder framework. The fingers 103 are curved and somewhat longer than the fingers 104, the latter being short to permit the pockets to pass the feeder and the former being yieldably mounted to permit passage of all of the pockets and car-

tons delivered into alternate ones of the same. The fingers 103, 104 provide a restricted guide that acts to open the cartons successively advanced therethrough by the knife 101 into the pockets 41.

5 The fingers 103 are fixed on a tubular shaft 144, in staggered relation with the carton supporting parts of the pocket, the shaft 144 in turn being journaled on a stationary shaft 105 mounted in any suitable manner on the framework of the feeder. A spring 106 on the shaft 105, has its opposite ends connected with said shaft and the shaft 144, and said spring yields sufficiently to provide for yielding movement of the fingers 103, but is strong enough to prevent yielding movement of said fingers when the carton is advanced therewith by the knife 101.

20 The knife 101 moves upwardly into the front carton of the stack, then forwardly to separate the carton therefrom and advance it between the opening fingers 103, 104, into one of the pockets 41. Thereafter, the knife moves downwardly, rearwardly, and upwardly into the next carton on the front of the stack. The last mentioned carton is then delivered by the knife through the opener into the next pocket 41, and these operations are repeated as the pockets 41, 41' successively pass the carton feeding mechanism.

25 The mechanism for continuously imparting the above described movements successively to the knife is preferably comprised by the following instrumentalities. Fixed in spaced relation on the continuously driven shaft 45, are a pair of cams 107, 107'. Each of these cams is provided on its opposite faces with cam grooves, the cam grooves of cam 107 being indicated at 108, 109, and the cam grooves of the cam 107' being indicated at 108', 109'. The vertical motion of the knife 101 is derived from the cam groove 108 which has engaged therein a roller 110 that is journaled on an arm 111 intermediate the opposite ends thereof. The arm 111, in turn, is journaled on a shaft 112 supported in any suitable manner by the frame 46. The lever 111 has its free end pivotally connected with one extremity of a link 112a the opposite extremity of which is pivotally connected with the free end of an arm 113.

30 The arm 113 is fixed on a rockshaft 114 that is journaled in suitable bearings on the frame 46. Fixed on the rockshaft 114 is a second arm 115, the free end of which is pivotally connected with a link 116. The opposite extremity of this link is pivotally connected with a slide 117 which, through the described connections therefor with the cam grooves 108, is vertically reciprocated in a guide 118. This guide 118 is secured to a second guide 119 that is adapted to be horizontally reciprocated along a way or guide 120 bolted or otherwise suitably secured to the cross member 89.

35 Fixed on the upper end of the slide 117 is a holder 121 on which is pivoted, as at 122, a substantially L-shaped bracket 123. The knife 101 is bolted or otherwise suitably secured on the substantially vertical leg of this bracket, the horizontal leg thereof extending between a set screw 124 and a spring 125 that provides for limited yielding movement of the knife 101 when it engages the rear wall of the carton on the inner face thereof. The set screw 124, serves to regulate the yielding movement of the knife and is carried by a bracket 126 secured to or formed integrally with the holder 121. The spring 125 is interposed between said holder and the horizontal arm of the bracket 123 and retained against displacement in any suitable manner.

40 It was previously pointed out that the knife 101 moves rearwardly into engagement with the inner face of the rear wall of the carton. For the latter purpose, the cartons are each formed in a manner well understood in the art, with one flap shortened to permit the knife to engage the rear wall of the carton as aforesaid.

45 The forward and rearward or horizontal reciprocating movement of the knife 101 is derived from the cam groove 109 in which is engaged a roller 127 that is journaled on an arm 128 intermediate the opposite ends thereof. The arm 128, in turn, is journaled on the shaft 112, and the free end of said arm is pivotally connected with one extremity of a link 129. The opposite extremity of the link 129 is pivotally connected with the free end of an arm 130 forming part of a bell crank that is journaled on the shaft 114. The other part or arm 131 of this bell crank has its free end pivotally connected with one extremity of a link 132. The opposite extremity of the link 132 is pivotally connected with the slide 119 which, through its described connections with the cam groove 109, is reciprocated horizontally to thereby impart like motion to the knife 101.

50 The pockets 41, 41' supplied with cartons by the feeders 79, 80, respectively, carry said cartons in succession past means for recollapsing the same. This recollapsing means (Fig. 2) is similar in construction to that described in my copending application Serial No. 351,930, filed April 2, 1929, and includes a recollapsing element 133 extending angularly to and across the path of travel of the 120 pockets in staggered relation with the parts 57, 58 thereof. The element 133 is bent rearwardly and angularly as at 134 to engage the cartons and recollapse them in the pockets. It will be remembered that the parts 125 57 of the pockets are closed by the springs 62 when they have traveled past the second carton feeding mechanism 80. In order to provide for collapsing of the cartons in the pockets, however, the parts 58 thereof are 130

actuated rearwardly in a manner to be presently described and during rearward movement of the parts 57, the collapsed cartons are supported against displacement from the pockets by engagement of the parts 57, 58 with diagonally opposed corners of the cartons.

As each pocket with a carton supported therein approaches the recollapsing means, the roller 68 on the arm 67 of said pocket, engages a fixed cam rail 135 supported in any suitable manner transversely of, and below the path of travel of the pockets. Engagement of the roller 68 with said cam rail 15 swings the rear parts 58 of the pocket in a clockwise direction (Fig. 2). The forward part of the cam rail 135 terminates in an abruptly and outwardly directed portion 136, and when the roller 68 is disengaged therefrom, rear parts 58 of the pocket are closed 20 by the spring 63 and reopen the carton in the pocket.

The reopened cartons are successively transferred from the pockets onto the successive holders or forms 39 of the carton sealing machine, and any suitable means may be employed for so transferring the cartons. As herein disclosed, the parts 58 of the pockets are provided with bosses 58' in which are slidably mounted vertical rods 137 that are retained against rotation by any suitable means for this purpose. Mounted on the rods 137 are springs 138 which, through engagement of their opposite ends with the top parts 58 and horizontally extending arms 139 fixed on the upper ends of the rods 137, normally tend to hold said rods and arms in raised position.

The arms 139 have secured to or formed 40 integrally therewith, depending holders 140, on the lower ends of which are bolted or otherwise suitably secured, strippers 141 that are normally raised above the pockets. These strippers are adapted to be moved downward- 45 ly and successively transfer the cartons from the pockets 41, 41' to the successive elements 39 of the carton sealing machine. For this purpose, the rods 137 have mounted on the lower ends thereof, rollers 142 successively 50 adapted to engage an inclined cam rail 143 that successively lowers the strippers and likewise transfers the cartons from the successive pockets onto the successive forms or supports 39. The cam rail 143 is supported 55 in any suitable manner by the machine framework and when the rollers 142 are successively disengaged from the lower forward end of said cam rail, the rods 137 and strippers 141 are likewise raised through the action of the 60 springs 138.

The operation of the machine will be readily understood from the foregoing and may be briefly summarized as follows. The pockets 41, 41' are opened before they reach the 65 carton feeding mechanism 79, and as said

pockets travel past said mechanism, the latter successively delivers opened cartons into the alternate pockets 41. The alternate pockets 41' remain open and receive cartons from the carton feeding mechanism 80, whereupon the latter pockets are closed as they travel forwardly of said mechanism. The pockets 41 traveling past the carton feeding mechanism 80 remain closed and the pockets 41, 41' all travel successively past the recollapsing means 68 which successively recollapses the cartons as previously described. Each pocket is opened by the cam 135, to provide for collapsing of the cartons therein, whereupon the pocket is closed to reopen the carton 80 therein. The reopened cartons are then successively transferred by the strippers 141 to successive supports or forms 39 of the carton sealing machine conveyor.

It will appear from the foregoing, that by 85 increasing the number of cams and pockets, any desired number of carton feeding mechanisms can be provided to supply the pockets with cartons. It will further appear, that devices embodying the present invention may 90 be associated singly or together with any instrumentality to which it is desired to feed cartons.

It is therefore to be expressly understood that the invention is not limited to the embodiment thereof herein disclosed, or otherwise than by the terms of the appended claims.

What is claimed is:

1. In a carton feeding machine, a plurality of mechanisms each adapted to open and advance cartons, and a plurality of pockets all movable past each of said mechanisms and adapted to selectively receive the open cartons advanced thereby.

2. In a carton feeding machine, a pair of mechanisms each adapted to open and advance cartons, and a plurality of pockets all movable past both of said mechanisms and alternately receiving the open cartons advanced thereby respectively.

3. In a carton feeding machine, a pair of mechanisms each adapted to open and advance cartons, and a plurality of pockets all movable along a closed path past both of said mechanisms and alternately receiving the open cartons advanced thereby respectively.

4. In a carton feeding machine, a plurality of means each adapted to feed cartons successively from one of a plurality of carton supplies, and a plurality of continuously moving carton supporting pockets arranged to travel past said plurality of means and adapted to receive the cartons therefrom.

5. In an apparatus of the character described, a plurality of means each adapted to feed cartons successively from one of a plurality of carton supplies, a carton sealing machine, means for carrying cartons successively from the plurality of means to the

- carton sealing machine and comprising a plurality of movable carton supporting pockets adapted to receive the cartons from said plurality of means, and means for transferring the cartons successively from said pockets to said carton sealing machine.
6. In an apparatus of the character described, a plurality of means each adapted to feed and open cartons successively, a carton sealing machine, means for carrying the open cartons from the plurality of feeding and opening means to the carton sealing machine and comprising a plurality of continuously moving carton supporting pockets adapted to receive the open cartons from said feeding and opening means, and means for transferring the cartons successively from said pockets onto successive continuously traveling elements of said carton sealing machine.
- 10 7. In an apparatus of the character described, a plurality of means each adapted to feed cartons from one of a plurality of carton supplies, a carton conveyor, means for carrying the cartons from the plurality of feeding means to the carton conveyor and comprising a plurality of movable carton supporting pockets each adapted to receive a carton from one of said plurality of feeding means, and means for transferring the cartons successively from said pockets to said carton conveyor.
- 15 8. In an apparatus of the character described, a plurality of means each adapted to feed cartons successively, a carton conveyor, means for carrying the cartons successively from the plurality of feeding means to the carton conveyor and comprising a plurality of movable carton supporting pockets adapted to receive the cartons from said plurality of feeding means, means arranged between the carton feeding means and the conveyor and adapted to successively collapse cartons supported in the pockets, means forming opposed parts of the pockets relatively movable to provide for collapsing and reopening of the cartons supported therein, and means for transferring the reopened cartons successively from the pockets to said carton conveyor.
- 20 9. In a carton feeding machine, a plurality of movable carton supporting pockets adapted to travel continuously one after another along a closed path, and a plurality of carton supply and feeding means arranged adjacent the path of travel of the pockets and adapted to deliver cartons into said pockets selectively.
- 25 10. In a carton feeding machine, an endless chain or belt having a plurality of carton supporting pockets fixed thereon, means for imparting motion to said chain or belt and said pockets, and two carton feeding mechanisms disposed at opposite sides of the chain or belt respectively and each adapted to deliver cartons into alternate pockets on the chain or belt.
- 30 11. In a carton feeding machine, an endless chain or belt having all of its reaches disposed in a substantially horizontal plane, a plurality of carton supporting pockets secured on the chain or belt to travel therewith, means for imparting motion to the chain or belt and said pockets, and a pair of carton feeding mechanisms arranged at opposite sides of the chain or belt respectively and each adapted to deliver cartons into alternate pockets on the chain or belt.
- 35 12. In an apparatus of the character described, an endless chain or belt, a plurality of carton supporting pockets secured on the chain or belt to travel therewith, means for imparting motion to the chain or belt and said pockets, a pair of carton feeding mechanisms arranged at opposite sides of the chain or belt respectively and each adapted to deliver cartons into alternate pockets on the chain or belt, a carton conveyor at one end of the chain or belt, and means for transferring the cartons successively from the pockets to said carton conveyor.
- 40 13. In a carton feeding machine, a plurality of carton feeding mechanisms, a plurality of carton supporting pockets each arranged to travel past all of said feeding mechanisms and adapted to be opened and closed, means for opening each pocket adjacent one of the feeding mechanisms to receive a carton therefrom, and means for closing the pockets on the cartons therein.
- 45 14. In a carton feeding machine, a plurality of carton feeding mechanisms, a plurality of carton supporting pockets each arranged to travel past all of said feeding mechanisms and adapted to be opened and closed, levers on the pockets, cam means for operating the levers to open each pocket adjacent one of the carton feeding mechanisms and provide for delivery of a carton from said mechanism into the pocket, and spring means for closing the pockets on the cartons therein.
- 50 15. In a carton feeding machine, a plurality of continuously traveling carton supporting pockets adapted to be opened and closed, a plurality of carton supply and feeding mechanisms for delivering cartons into the pockets selectively, and means for selectively opening and closing said pockets.
- 55 16. In a carton feeding machine, a plurality of movable carton supporting pockets arranged to travel one behind another and adapted to be opened and closed, a plurality of carton supply and feeding mechanisms for delivering cartons into the pockets selectively, and means for selectively opening and closing said pockets.
- 60 17. In a carton feeding machine, a plurality of movable pockets adapted to be opened and closed, a pair of carton feeding mechanisms each adapted to deliver cartons into

alternate pockets, and means for opening and closing the pockets to receive and grip the cartons therein respectively.

18. In a carton feeding machine, a plurality of movable pockets adapted to be opened and closed, a pair of carton feeding mechanisms each adapted to deliver cartons into alternate pockets, means for opening the pockets traveling past the first carton feeding mechanism and adapted to hold alternate pockets open until they have traveled past the second carton feeding mechanism, means for closing alternate pockets after they have received cartons from the first carton feeding mechanism, and means for closing alternate pockets after they have received cartons from the second carton feeding mechanism.

19. A carton feeding machine including a plurality of pockets arranged to travel one after another along a closed path and a plurality of feeding mechanisms at opposite sides of said path and each adapted to deliver cartons in the pockets selectively as they travel past said mechanisms.

20. A carton feeding machine including a series of pockets travelling continuously one after another along a closed path and a pair of carton feeding mechanisms each adapted to deliver cartons from one of a pair of carton supplies in alternate pockets of said series respectively.

21. A carton feeding machine including a plurality of pockets travelling continuously one after another along a closed path and a plurality of means past each of which all of the pockets travel and each adapted to deliver open cartons in the pockets selectively as said pockets move in succession past said plurality of means.

22. In an apparatus of the character described, a plurality of mechanisms each adapted to feed cartons successively from one of a plurality of supplies thereof, and a plurality of pockets all travelling continuously past each of said mechanisms and selectively receiving the cartons fed thereby.

23. In an apparatus of the character described, a plurality of mechanisms each adapted to open and advance cartons, a plurality of pockets all travelling continuously past each of said mechanisms and selectively receiving open cartons advanced thereby, and means for successively removing the cartons from said pockets.

24. In an apparatus of the character described, a plurality of mechanisms for separating, opening, and advancing cartons, a plurality of pockets all movable past each of said mechanisms and adapted to selectively receive open cartons separated and advanced thereby, and means for removing the open cartons from the pockets successively.

25. In an apparatus of the character described, a plurality of mechanisms each supplying cartons successively, a plurality of

pockets all movable past each of said mechanisms and selectively receiving the cartons supplied thereby, a movable device adjacent the path of travel of the pockets, and means for transferring the cartons from said pockets successively to said movable device.

26. In an apparatus of the character described, a plurality of mechanisms each adapted to supply open cartons successively, a series of pockets all movable one after another past each of said mechanisms and adapted to selectively receive the cartons supplied thereby, means for removing the open cartons from the pockets successively, and a movable device onto which the cartons are delivered successively by said means.

27. In an apparatus of the character described, a plurality of mechanisms each adapted to supply cartons successively, an endless series of pockets all movable past each of said mechanisms and into which the cartons are delivered selectively thereby, means for removing the cartons from the pockets successively, and a movable device on which the cartons are successively delivered by said means.

In testimony whereof I have signed this specification.

CHARLES F. RICHARD.
